WALL PLATE

Raymond U. H. Tegner, Rockford, Ill., assignor to
Amerock Corporation, Rockford, Ill.

Filed May 26, 1969, Ser. No. 17,351

Term of patent 14 years

Int. Cl. D13—99; D8—99

U.S. Cl. D8—179

Fig. 6

Fig. 7

Fig. 8

Fig. 9

Fig. 10

FIG. 1 is a front view of a wall plate wherein my design resides in the switch plate shown.

FIG. 2 is a side view of the plate as seen from the right in FIG. 1.

FIG. 3 is a sectional view taken along the line 3—3 in FIG. 1.

FIG. 4 is a top view of the plate shown in FIG. 1.

FIG. 5 is a sectional view taken along the line 5—5 in FIG. 1.

FIG. 6 is a front view of a wall plate wherein my design resides in the electrical outlet plate shown.

FIG. 7 is a side view of the plate as seen from the right in FIG. 6.

FIG. 8 is a sectional view taken along the line 8—8 in FIG. 6.

FIG. 9 is a top view of the plate shown in FIG. 6.

FIG. 10 is a sectional view taken along the line 10—10 in FIG. 6.

FIG. 11 is a front view of a wall plate wherein my design resides in the double switch plate shown.

FIG. 12 is a side view of the plate as seen from the right in FIG. 11.

FIG. 13 is a sectional view taken along the line 13—13 in FIG. 11.

FIG. 14 is a top view of the plate shown in FIG. 11.

FIG. 15 is a sectional view taken along the line 15—15 in FIG. 11.

FIG. 16 is a front view of a wall plate wherein my design resides in the combined switch and electrical outlet plate shown.

FIG. 17 is a side view of the plate as seen from the right in FIG. 16.

FIG. 18 is a sectional view taken along the line 18—18 in FIG. 16.

FIG. 19 is a top view of the plate shown in FIG. 16.

FIG. 20 is a sectional view taken along the line 20—20 in FIG. 16.

FIG. 21 is a sectional view taken along the line 21—21 in FIG. 16.

FIG. 22 is a front view of a wall plate wherein my design resides in the triple switch plate shown.

FIG. 23 is a side view of the plate as seen from the right in FIG. 22.

FIG. 24 is a sectional view taken along the line 24—24 in FIG. 22.

FIG. 25 is a top view of the plate shown in FIG. 22.

FIG. 26 is a sectional view taken along the line 26—26 in FIG. 22.

I claim:

The ornamental design for a wall plate, as shown and described.
